CLAIM

The ornamental design for a clip for disc brakes, as shown and described.

DESCRIPTION

FIG. 1 is a perspective view showing a clip for disc brakes in accordance with my design;

FIG. 2 is a top plan view thereof;

FIG. 3 is a front elevational view thereof;

FIG. 4 is a side elevational view thereof, the opposite side being a mirror image of FIG. 4;

FIG. 5 is a rear elevational view thereof; and,

FIG. 6 is a bottom plan view thereof.

FIG. 4

FIG. 5

FIG. 6
